UNITED STATES PATENT OFFICE.

WILLIAM VON ELM, OF BROOKLYN, NEW YORK.

DESIGN FOR A JELLY MOLD OR SIMILAR ARTICLE.

Application filed November 17, 1927. Serial No. 24,186. Term of patent 7 years.

To all whom it may concern:

Be it known that I, WILLIAM VON ELM, a citizen of the United States, residing at Brooklyn, in the county of Kings and State of New York, have invented a new, original, and ornamental Design for Jelly Molds or Similar Articles, of which the following is a specification, reference being had to the accompanying drawing, forming part thereof.

Fig. 1 is a perspective view of the article showing my new design, and

Fig. 2 is a similar view of the article inverted.

I claim:

The ornamental design for a jelly mold, or similar article, as shown.

WILLIAM VON ELM.
